RECEIVER CHASSIS FOR TOUR GUIDE SYSTEMS

Anthony S. Valente, Bernardsville, N.J., assignor to
Telesonic Systems Inc., Fairfield, N.J.

Filed Oct. 31, 1974, Ser. No. 519,715

Term of patent 14 years

Int. Cl. D14—03

U.S. Cl. D26—14 K

FIG. 1

FIG. 2

FIG. 3

FIG. 4

FIG. 5

FIG. 1 is a front view of a receiver chassis for tour guide systems, embodying my new design;

FIG. 2 is a side elevational view thereof;

FIG. 3 is a rear elevational view thereof;

FIG. 4 is a top plan view thereof; and

FIG. 5 is a bottom plan view thereof.

I claim:

The ornamental design for a receiver chassis for tour guide systems, as shown.
